TRUSS

Frank B. Lane, deceased, late of Paragould, Ark.,
by Harry I. Lane, administrator, Conway, Ark.,
assignor to Lifetime Truss Company, Inc.,
Jonesboro, Ark.

Original application June 11, 1941, Serial No.
397,610. Divided and this application March 6,
1943, Serial No. 478,268

3 Claims. (Cl. 128—96)

This is a divisional application of applicant's co-pending application Serial No. 397,610, filed June 11, 1941.

The present invention relates to new and useful improvements in trusses and has for its primary object to provide a spring wire clamping member adapted for partly encircling the body of a person and provided with substantially duplicate truss pads at each end of the wire for engaging the rupture with one pad for the purpose of pressing the protruding part of the rupture inwardly and upwardly in its normal position, while the pad on the other end of wire is positioned against the back of the person and serves to retain the wire against slipping.

A further object of the present invention is to provide novel means for attaching the truss pad and the back pad to the ends of the wire.

A still further object is to provide ventilating means for the truss pad and the back pad.

An additional object is to provide a device of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a front elevational view of the invention in position on a person.

Figure 2 is a plan view of the pad.

Figure 3 is a sectional view taken along a line 2—2 of Figure 1.

Figure 4 is a perspective view of one end of the body encircling spring clamping wire, and

Figure 5 is a perspective view of the locking pin.

Referring now to the drawing in detail, the truss pad is designated generally at 18 which is composed of a plurality of concentric rings 19 of successively reduced diameter and formed of hard rubber or plastic material. Each ring is of channel form with the edges 20 of the channel rolled inwardly to form a restricted opening 21 on one surface of the ring and within which is fitted a soft rubber ring 22, the sides of the ring 22 being gripped by the edges 20 of the restricted opening to retain the ring 22 in position.

The rings 19 are provided with aligned radial

openings 23 adapted to receive one end of a spring wire member 24 adapted to partly encircle the body of a person, the member 24 being retained in position by a locking pin 25 also inserted 5 through aligned radial openings 26 in the rings 19 in crossed relation to the member 24.

The wire member 24 is formed with a notch 27 in which the pin 25 is seated to prevent removal of the member 24 from the rings. The member 10 24 may be released from the locking pin by a partial rotation of the member, or by removing the locking pin and the member 24 then withdrawn from the pad.

Each end of the wire member 24 may be provided with one of the pads 18 so that one pad may be positioned over a rupture at the front of the body of a person and the other pad pressed against the back of the person to retain the pads and wire member in position on the body.

20 Between the front and rear pads, the wire member 24 is covered with a rubber tubing 28.

It is believed the details of construction, advantages and manner of use of the device will be readily understood from the foregoing without 25 further detailed explanation.

What is claimed is:

1. A truss comprising a pad composed of a plurality of spaced concentric rings of molded material, a rigid backing ring attached at the rear of each of said rings, a wire member having one end inserted radially through each of the backing rings and adapted to partly encircle the body of a person, and means for releasably securing the end of the member in said rings.

35 2. A truss comprising a plurality of spaced concentric rigid rings each having an annular channel in one surface of the ring, a soft rubber ring secured in the channel of each rigid ring, a wire member extending radially of the rings and a locking pin also extending radially of the rings in crossed relation to said wire member for securing the rings in assembled position on the member.

40 3. A truss pad comprising a plurality of spaced concentric ring members, and elongated members extending radially of the ring members in crossed relation to each other, said elongated members having interfitting engagement at their point of crossing.

45 HARRY I. LANE,
Administrator of the Estate of Frank B. Lane,
Deceased.
